ABRASIVE DISK

Frank Osbern Albertson, Sioux City, Iowa, assignor to Albertson & Company, Inc., Sioux City, Iowa, a corporation of Iowa

Application June 12, 1944, Serial No. 539,896

1 Claim. (Cl. 51—195)

This invention relates to abrasive disks, and more particularly to that type of abrasive disk that is capable of being mounted upon and driven with a so-called surfacing pad or rotary head characterized by a yielding circular part contacting the back or inner face of the disk, a centrally located centering hub, and a plurality of locking wings disposed adjacent to the centering hub. Generally speaking, an abrasive disk intended for use with a surfacing pad or rotary head so characterized consists of a relatively stiff circular backing piece having a coating of abrasive particles bonded to its front or outer face, a central aperture for receiving the centering hub, and slots radiating from the central aperture to receive the locking wings.

Hitherto it has been the practice to distort the slot sides in threading the locking wings into and out of the slots, and in some instances it has been the practice to provide the abrasive disk with comparatively large holes, in which the outer ends of the slots terminate, in order to prevent radial tearing resultant from strain thrown upon the slot edges from becoming so extended as to destroy the disk. These practices of the prior art have been far from satisfactory even when the slotted central portion of the disk has been devoid of any abrasive coating, and have been definitely unsatisfactory in respect of disks having their front faces covered with resin bonded abrasive particles. A resin bonded abrasive overlying the backing piece at the slot sides renders volitional distortion of the slot sides difficult and very undesirable because tending greatly to minimize the total service the disk is capable of rendering.

A salient object of my invention is to provide an abrasive disk, of the centrally apertured radially slotted type that practicably may have its entire front or outer face completely covered with a resin bonded abrasive, having slots into and from which the locking wings readily may be threaded without distortion of the slot sides despite that the slots are capable of cooperating with the locking wings to prevent objectionable lost-motion between the abrasive disk and the pad.

Another object of my invention is to have the slots present extensive straight "on center" sides for driven engagement with the locking wings.

In the accompanying sheet of drawings illustrating my invention:

Fig. 1 is a front face view, somewhat in perspective, of an abrasive disk embodying my present invention;

Fig. 2 is a front face view of the abrasive disk with a portion thereof broken away to reveal the surfacing pad or rotary head whereon the disk is operatively mounted; and

Fig. 3 is an enlarged fragmentary view, generally similar to Fig. 2, in which the driving wings have been depicted in section to reveal the extensive "on center" sides of the slots which are in driven engagement with such wings.

Similar characters of reference refer to similar parts throughout the several views.

The abrasive disk comprises a circular backing piece 10 of fiber, cardboard, cloth or other suitable material having its front or outer face completely covered with abrasive particles 11 that preferably have been adhered to the backing piece by a suitable binder in the nature of a synthetic phenolic resin.

The abrasive disk is intended for use, in surfacing operations, with a conventional surfacing pad or rotary head comprising the rigid power driven central portion 12, the flexible marginal portion 13, the centering hub 14, carried by the central portion 12, and the locking wings 15—15 also carried by the central portion 12. There may be but two of the locking wings 15 as shown, in which case they are diametrically opposite with reference to the centering hub 14. However, if desired, there may be four of the locking wings 15 equidistantly spaced around the centering hub 14. The base portions of the locking wings 15 are anchored in any suitable fashion to the portion 12. Such locking wings extend radially with respect to hub 14. They also extend for short distances at right angles to that face of portion 12 to which they are anchored and are then turned to extend circumferentially of and parallel with the front face of the surfacing pad with the free end of each locking wing trailing with reference to the direction of pad rotation.

Referring again to the abrasive disk, it is provided with a central circular aperture 16 to receive the centering hub 14. It is also provided with slots 17 to receive the locking wings 15. Each slot 17 merges into the aperture 16 and is defined by two comparatively long straight sides 18 and 18a joined by a curved side 19, which preferably is struck from a center located within the slot. Each straight side 18 is truly radial or "on center" with respect to the aperture 16—and with respect to the centering hub 14 when the abrasive disk is properly mounted upon the surfacing pad as depicted in Figs. 2 and 3. Consequently, the straight sides 18 and 18a of each slot 17 are comparatively close together at the

inner end of the slot and are substantially spaced apart at the outer end of the slot, and each slot is adapted to have its straight side 18 in continuous driven contact with one of the locking wings 15 throughout a line as long as the wing is wide.

These features of my abrasive disk maximize the total surfacing service it is capable of rendering, because (a) enabling application of the disk to the surfacing pad, and its removal therefrom, without any distortion of the slot sides in so doing, while preventing objectionable circumferential lost-motion between the abrasive disk and the surfacing pad, and (b) ensuring substantial contact, in lines "on center" with the axis of disk and pad rotation, between each locking wing and the slot side in respect of which such wing is in driving relationship.

Having thus illustrated and described my invention, what I claim as new and desire to secure by Letters Patent of the United States is:

An abrasive disk adapted to be mounted on a surface pad including a centering hub and a plurality of disk holding and driving wings each hav-

ing radially disposed disk driving portions adjacent the hub and substantially perpendicular to the surface pad, and disk holding portions in spaced and substantially parallel relation to the surface pad, said abrasive disk comprising a relatively stiff circular backing sheet with a coating of abrading particles on one face thereof, said abrasive disk also having a central aperture for receiving the centering hub of the surface pad and a plurality of slots extending outwardly from the central aperture to receive the driving portions of said wings, each of said slots being symmetrical about a radial axis and having outwardly diverging, radial, straight sides terminating in an arcuate surface tangent to said sides at their outer ends so that the slots are devoid of sharp corners, said straight sides being relatively close together where the slot merges into the central aperture and being of a length practically equal to that of said driving portions of the wings so as to have full length engagement with said driving portions.

FRANK OSBERN ALBERTSON.
